UNITED STATES PATENT OFFICE.

JOHN KRALUND, OF BROOKLYN, NEW YORK, ASSIGNOR TO DOEHLER DIE CASTING COMPANY, OF BROOKLYN, NEW YORK, A CORPORATION OF NEW YORK.

GATE-FORMER FOR CASTING APPARATUS.

1,321,457.

Specification of Letters Patent. Patented Nov. 11, 1919.

Application filed July 9, 1919. Serial No. 309,575.

To all whom it may concern:

Be it known that I, JOHN KRALUND, a citizen of the United States, residing in the borough of Brooklyn, in the city of New York, county of Kings, and State of New York, have invented certain new and useful Improvements in Gate-Formers for Casting Apparatus, of which the following is a specification.

10 My invention relates to an improved construction of gate former for casting apparatus, and particularly die casting apparatus. My invention is particularly designed for use in connection with the casting apparatus disclosed in my Patent No. 1,299,738, issued April 8, 1919, on die casting apparatus, although it is not limited strictly to action with such apparatus.

In the apparatus described in my said patent, molten metal is transferred from its container to the die by means of a moving carrier or ladle, the mouth-piece of which moves into connection with an opening extending through a gate member. Com-25 pressed air or the like then forces the metal through this opening into a die which may be secured to or positioned adjacent to the gate member. A bushing ordinarily extends through the opening in the gate member, and 30 is provided with a tapered forward end with which the mouth piece of the carrier device registers when the metal is to be delivered to the die. The bushing referred to, or gate former, as it is termed, has, in usual 35 practice, to be frequently renewed, because of burning of the same by the molten metal which passes therethrough.

My invention overcomes this difficulty by a construction embodying a jacket for a 40 cooling medium, such as water, surrounding the tube through which the molten metal passes, together with means for circulating a cooling medium therethrough, so that the temperature of the inner tube will be pre-45 vented from becoming excessively high, so that the necessity for renewing the bushings or gate formers will be largely obviated.

In order that a clearer understanding of my invention may be had, attention is here-50 by directed to the accompanying drawings forming part of this application and illustrating one embodiment of my invention. In the drawings, Figure 1 represent a vertical section through a gate member provided

with my invention; and Fig. 2 is a cross 55 section taken on line 2—2 of Fig. 1.

Referring to the drawings, the gate member 1 is shown broken away. This gate member is provided with a horizontal opening therethrough within which is mounted 60 an outer shell or tube 2. An inner shell or tube 3 is mounted within the outer shell 2. The outer tube 2 is provided with a portion 2^a having an inner surface of greater diameter than the remaining portion 2^b of the 65 tube. The inner tube 3 preferably is mounted with a forced fit within the portion 2^b of reduced diameter of the outer shell, an annular space 4 being provided between the 70 outer surface of the inner shell and the inner surface of the portion 2^a of the outer shell.

The outer tube 2 is provided with an enlarged head portion 5 which is adapted to engage against a face of the gate member 1. 75 This head is preferably provided with shoulders 6 so that it may conveniently be manipulated by a wrench in adjusting the tube into position. The head 5 has an opening therethrough, as is indicated at 7, 80 of the same diameter as that of the opening through the portion 2^b of tube 2, so that the inner tube 3 will have a forced fit bearing within the head 5 and within the portion 2^a of tube 2, at opposite ends of the 85 annular space 4. The annular space is thus made water-tight, the tube 2 constituting a water jacket surrounding the inner tube or gate former 3.

The head 5 is preferably provided with a 90 recess 8 in its face, of the same diameter as the shouldered portion 9 on the end of the inner tube 3, so that this shoulder fits within the recess 8 with a forced fit, the shoulder acting as a stop to prevent the inner 95 tube 3 being driven too far into the tube 2.

The inner end of tube 3 is preferably provided with a tapered seat 10, within the shouldered portion 9 and communicating with the bore of the tube. This seat is 100 adapted to receive the mouth piece 11 of a carrier device 12 which is adapted to carry molten metal from a melting pot or container into alinement with the gate former, after which compressed air or the like may 105 be used to force the charge of molten metal through the tube 3 into the die which may be secured to the opposite face of the gate

member 1 in alinement with the opening through tube 3. The details of construction of the metal carrier device are not material to the present invention. A suitable arrangement, however, is described and claimed in my Patent No. 1,299,738 previously referred to.

The gate former or tube 3 is cooled by the circulation of a suitable cooling medium, such as water; through the annular space 4. This circulation may be provided by means of a pair of tubes 13 and 14, which may be flexible hose or the like, one of the same serving for leading water into the space 4 and the other serving for returning the same therefrom. The tubes 13 and 14 are screwed into suitable tapped openings 15 and 16 extending into the head 5, these tapped openings being connected by passages 17 and 18 with the annular space 4.

It will be evident that the tube or gate former 3 will be cooled to a considerable extent by the circulation of water in the space 4, the heat imparted to the tube 3 by the molten metal passing therethrough being to a considerable extent carried away by the cooling fluid. The life of the gate former is, therefore, considerably extended. In adjusting the device it is only necessary to force the outer tube into place and to drive the inner tube into the outer tube until the shoulder 9 engages within recess 8. The inner and outer tubes may readily be removed by driving the same out of the opening in gate member 1, in the opposite direction to that in which they were forced into the opening in gate member 1.

What I claim is:—

1. In casting apparatus, the combination of a gate member having an opening therethrough, a jacket surrounding said opening, and means for circulating a cooling medium through said jacket, the forward end of said opening being adapted to receive the mouthpiece of a molten metal carrier. 40

2. In casting apparatus, the combination of a gate member having an opening therethrough, a tube extending through said opening, a second tube surrounding said first tube in said opening, so as to provide 50 an annular space between them, and connections for circulating a cooling medium through said space. 45

3. In casting apparatus; the combination of a gate member having an opening therethrough, a tube extending through said opening, having an enlarged head adapted to contact against a face of said gate member, and having portions of greater inner diameter and portions of reduced inner 60 diameter, an inner tube extending through said first tube with a tight fit in said portions of reduced diameter, an annular space being thereby provided between said inner tube and the portions of greater inner diameter of said outer tube, and connections for 65 circulating a cooling medium through said space. 55

This specification signed and witnessed this 26th day of June, 1919.

JOHN KRALUND.
